UNITED STATES PATENT OFFICE.

REUBEN S. HARPER, OF MILFORD, MICHIGAN.

DESIGN FOR A KNIFE.

SPECIFICATION forming part of Design No. 33,031, dated July 31, 1900.

Application filed June 23, 1900. Serial No. 21,386. Term of patent 7 years.

To all whom it may concern:

Be it known that I, REUBEN S. HARPER, a citizen of the United States, residing at Milford, in the county of Oakland and State of Michigan, have invented and produced a new and original Design for a Knife, of which the following is a specification, reference being had to the accompanying drawings, forming a part thereof.

10 In the drawings, Figure 1 is a perspective view of a knife embodying my new design. Fig. 2 is a bottom plan view of the same.

As shown in the drawings, the main feature of my design consists of a blade having the 15 cutting edge thereof segmentally curved, the edge of said blade opposite said curved or cutting edge being provided with a tang, on which is secured a handle. Said blade at one end thereof is curved laterally to provide a 20 curved cutting edge transverse of the main

cutting edge and a secondary cutting edge parallel with said main cutting edge at one end thereof or approximately so, as shown in Fig. 2.

The cutting-blade is made very thin and is, 25 as shown, brought to a keen edge. The outer surface of said blade is smooth and relatively straight from the edge upward.

Having described my invention, what I claim as new, and desire to secure by Letters 30 Patent, is—

A design for a knife as herein shown and described.

In testimony whereof I have signed my name to this specification in the presence of 35 two witnesses.

REUBEN S. HARPER.
